UNITED STATES PATENT OFFICE.

GUSTAF SYLVAN, JOHANNES B. SYLVAN, AND EMIL WILHELM SYLVAN, OF COLUMBIA, SOUTH CAROLINA.

CLOCK-MOVEMENT.

No. 884,961.

Specification of Letters Patent.

Patented April 14, 1908.

Application filed September 13, 1907. Serial No. 392,727.

To all whom it may concern:

Be it known that we, GUSTAF SYLVAN, JOHANNES B. SYLVAN, and EMIL WILHELM SYLVAN, citizens of the United States, residing at Columbia, in the county of Richland and State of South Carolina, have invented a new and useful Improvement in Clock-Movements, of which the following is a specification.

10 In another application for a patent filed by us of even date herewith, Serial No. 392,726, we have shown and described a clock movement which has for its object to provide means for securing a more uniform transmission of power from the main spring to the escapement, it being well known that the main spring when fully wound up exerts a greater power than when nearly run down. The improvement consisted in interposing an 15 intermediate coil spring in the train of gears which was intermittently wound up by the main spring at regular intervals and which intermediate spring expended its derived power in operating the clock escapement.

20 Our present invention has the same object in view and employs some of the same instrumentalities, but comprises the novel means for controlling the automatic winding action through the recurrent action of the striking 25 mechanism of the clock, as will be herein-after more fully described with reference to the drawings, in which

Figure 1 is a side view of a clock movement with our invention shown applied. Fig. 2 is 35 an edge view looking from right to left in Fig. 1. Fig. 3 is a sectional view of the intermediate spring and its associated parts. Fig. 4 is an inside view of the stop plate and stop lever. Fig. 5 is a section on line 5--5 40 of Fig. 1 and Fig. 6 is an edge view looking upwardly in Fig. 1.

In the drawing, Figs. 1 and 2, A represents the front and A' the back plate of the frame of the clock movement, between which the 45 various gears of an ordinary clock movement are contained.

A' is a supplemental front plate, shown in Fig. 2, but partly broken away in Fig. 1, and between which and the usual front plate A 50 the principal parts of our attachment are contained.

B is the usual main spring with barrel, winding shaft, ratchet and pawl. To this barrel, see Fig. 2, is attached the main drive 55 wheel 1 whose teeth mesh with and turn the

pinion 2. Ordinarily this pinion 2 transmits its power through the gear wheels 3, 4, 5, 6, 6^a, 7 and 7^a to the escapement C. In the present invention, however, the pinion 2 is not directly connected to the gear wheel 3, 60 but only indirectly through the interposition of the intermediate spring which is wound up intermittently by the main spring B and which intermediate spring transmits its derived power through the train of gears 3, 4, 5, 65 6, 6^a, 7 and 7^a to the escapement, so that the clock time mechanism is driven through the intermediate spring instead of by the main spring direct as hereafter more fully described. 70

The intermediate spring and its accessories are contained between the frame plates A and A', in Fig. 2, and the principal parts of it are shown detached in Figs. 3 and 5, in which 2 is the same pinion shown at 2 in Fig. 2 which is driven by the main gear 1 on the spring barrel. This pinion 2, Fig. 3, is rigidly attached to a shaft a which on its outer end has a squared portion a' fitting the squared hole of a spring barrel D' containing 80 the intermediate coil spring E which is of sufficient length and tension to run the clock through the predetermined intervals of its winding by the main spring. One end e², Fig. 5, of this spring is attached to the barrel D' and the other end e³ is attached to the hub of the gear wheel 3 which gear wheel is loose on the shaft a. One of the outer convolutions of this intermediate coil spring E is caught by a split or bifurcated pin b², Figs. 90 4 and 5, attached at right angles to a stop lever b on the outer side of spring barrel D'. This split pin plays in a slot d', Figs. 1 and 5, in the side of the spring barrel and has a motion to or from the center according as the 95 spring is wound up and constricted or relaxed and expanded. As seen in Figs. 5 and 3, the spring E is wound up and constricted and the split pin b² is nearest to the center of the shaft a and in the inner end of the slot d', 100 but when this spring is expanded and run down, the pin b² is forced by the outer convolution of the spring to go to the outer end of the slot d'. This movement of the pin b² from the center effects the unlocking of the 105 barrel of the intermediate spring E and the movement to the center effects the locking of the same as follows:

On the inner surface of the stationary cover plate A', Figs. 1, 3, and 4, are formed a 110

circular series of inturned lugs d and when the inner end of the stop lever b carrying pin b^2 is drawn to a position near the center, as seen in Fig. 5, the outer end of lever b will 5 strike against one of the stationary lugs d , as in Fig. 1, and stop the further winding of the intermediate spring E , but when the inner end of lever b carrying pin b^2 is moved outwardly, as by the unwinding and relaxation 10 of the spring E , then the outer end of lever b moves inward and out of range of the stop lugs d and allows the main spring to again wind up the intermediate spring.

It will be understood that as the main 15 spring winds up the intermediate spring intermittently, some means of releasing the main spring barrel is required, as well as means for stopping the same. In our other application for a patent herebefore referred 20 to, special releasing and stopping devices are provided for thus releasing and stopping the intermittent rotation of the main spring barrel. In our present invention, we cause the intermittent and recurrent action of the 25 striking devices to effect the release of the main spring barrel in order to enable it to perform its intermittent winding of the intermediate spring.

When the locking lever b has become released from its locking lug, the main winding gear 1 is then ready to assert its winding influence on the intermediate spring, but this movement does not occur until the striking begins to move, for the reason that the striking 30 gear is in locked engagement with the winding gears. When, however, the striking gear starts in the usual method of striking, the release which this effects on the main winding gear allows the latter to turn 40 and perform its function.

As the releasing devices for the winding action are dependent upon the striking mechanism of the clock, and as the striking mechanism runs very much longer in striking 12 45 than in striking 1 or 2, it is obvious that it is necessary to stop the time winding mechanism in some cases before the striking mechanism has finished its work, so the main time spring will be stopped without 50 straining the intermediate spring, and still allow the striking mechanism to go on and complete its work when striking the higher numbers. For this purpose, the releasing of the time mechanism is controlled by and 55 made contemporaneous with the starting of the striking mechanism, but is stopped independently of it by the stop devices already described, while the striking mechanism continues and completes its action. In effecting this, we connect, see Figs. 1 and 6, the main time gear 1 and the main strike gear 1^X by two equal gear wheels I and I' having two pinions i and i' . The pinion i' of I' , Fig. 6, is rigid with it and engages gear 60 1. The pinion i of I engages gear 1^X , but is

loose with respect to the gear I , and connected to it for rigid rotation in one direction by pawl p on flange f of wheel I and ratchet r rigid with pinion i . This, in the other direction, allows gear 1^X to turn pinion i and 70 ratchet r without turning the wheels I and I' . It will thus be seen that although gear 1^X , when it starts in the direction of the arrow, 75 will also turn I and I' and allow the starting of the main time gear 1, yet when the time gear is arrested after its initial movement by the stop devices described, the strike gear will continue turning to complete its striking by the free and independent movement allowed by the loose pinion and ratchet i r , but 80 the main time gear is held locked through the intermediate gears until the striking gear is released.

It will be seen that our invention presents in its general features a time train of gears, a 85 motor for actuating them in the form of an intermediate spring, a winding motor in the form of a main spring, and an intermittent releasing means for the winding motor in the form of the striking mechanism. This striking 90 mechanism, it will be understood, has the usual motor spring which is manually wound and is provided with a barrel and striking gears and by means of the devices described the winding motor is made to effectually 95 wind the intermediate spring of the time gear with the minimum movement of the striking gear, as in striking 1 o'clock and, in striking the higher numbers, the motion of the winding movement is arrested after the initial 100 movement, so that the striking gears can continue to turn and complete the striking of said high numbers.

We do not claim broadly the intermediate spring with its winding and stop mechanism, 105 as this is claimed in our co-pending application for a patent already referred to.

We claim

1. A movement for clocks and watches, comprising a striking mechanism, a main 110 spring, an escapement and a train of gears connecting the same, said train having interposed in it an intermediate coil spring arranged to be automatically wound at intervals by the main spring to actuate the escapement, a stopping mechanism for the automatic winding mechanism and a releasing mechanism connected to and controlled by the striking mechanism.

2. A movement for clocks and watches, 120 comprising a striking mechanism, a main spring, an escapement and a train of time gears connecting the same, said train having interposed in it an intermediate coil spring arranged to be automatically wound at intervals by the main spring to actuate the escapement, a stopping mechanism for the automatic winding mechanism and a releasing mechanism for the main spring connected 125 to and controlled by the striking mechanism, 130

and consisting of gears with ratchet and pawl connecting the time gears and striking gears, said stopping mechanism being arranged to arrest the time gears when the intermediate 5 spring is wound up and allow the striking gears to independently continue their action.

3. A movement for clocks and watches, comprising a striking mechanism, a main spring, an escapement and a train of time 10 gears connecting the same, said train having interposed in it an intermediate coil spring arranged to be automatically wound at intervals by the main spring to actuate the escapement, a stopping mechanism for the automatic winding mechanism consisting of a 15 lever having a pin at one end controlled by the expansion and contraction of the intermediate spring, and a stationary set of circumferential stops arranged to be engaged by the outer end of said lever when its inner end is drawn toward the center by the winding up of the intermediate spring, and a releasing mechanism for the main spring.

4. A movement for clocks and watches 20 comprising a time winding shaft with main spring and driving gear, a strike winding shaft with main spring and driving gear, intermediate gears connecting the main time

gear with the main strike gear, said intermediate gears being arranged to rotate together 30 in one direction and independently in the other direction, and an intermediate time spring arranged to be wound by the main time spring and to actuate the escapement and an automatic stop device for the time 35 gears arranged to come into effect when the intermediate spring is wound up.

5. A clock movement having a main spring, an intermediate secondary winding spring, stop devices for the same and a releasing mechanism controlled by the striking mechanism.

6. A combination in a clock or watch, of a time train, a motor for actuating the same, a winding motor for the train actuating motor, an intermittently acting striking device, and means connecting the striking device to the winding motor to release the latter and allow it to start into action.
